UNITED STATES PATENT OFFICE.

JOHN A. RIHL, OF PHILADELPHIA, PENNSYLVANIA, ASSIGNOR OF ONE-
THIRD TO ALBERT A. REDIFER AND ONE-THIRD TO THOMAS MAT-
LACK, OF PHILADELPHIA, PENNSYLVANIA.

LAST-BLOCK FASTENER.

No. 834,754.

Specification of Letters Patent.

Patented Oct. 30, 1906.

Application filed March 17, 1906. Serial No. 306,605.

To all whom it may concern:

Be it known that I, JOHN A. RIHL, a citizen of the United States, residing in Philadelphia, Pennsylvania, have invented certain Improvements in Last-Block Fasteners, of which the following is a specification.

One object of my invention is to provide improved means for adjustably securing the instep-piece to the body of a last-block, it being further desired to utilize the flexible cord for operating the fastening means to connect the instep-piece and said body for the purpose of preventing them from becoming separated.

These objects I secure as hereinafter set forth, reference being had to the accompanying drawings, in which—

Figure 1 is a perspective view of a last-block, showing my invention as applied thereto. Fig. 2 is a vertical section of the last-block shown in Fig. 1, illustrating my invention in detail; and Fig. 3 is an inverted plan of the instep-piece, further illustrating one of the detail features of my invention.

One frequent source of annoyance when working with last-blocks as hitherto known to the art has been due to the fact that the various means for detachably securing the instep-piece to the body of the block have been of such a nature that considerable time was necessarily expended in detaching said pieces, and, further, when a number of last-block bodies and instep-pieces were thrown together after use the parts constituting a complete last-block became separated, not only requiring considerable trouble and time in order to properly assemble the various sets, but also frequently resulting in the loss of the relatively small instep-pieces. By

my invention I overcome these various objectionable features, since I provide means whereby the catch for holding the instep-piece and the last-block body together may be instantly operated to separate said parts, and I so arrange this operating means that it is a practicable impossibility for the instep-piece and the last-block body to become separated.

Referring to the above drawings, A represents a last-block body having an instep-piece B fitted to it. This piece is detachably secured in position, partly by means of a dowel pin *a*, which fits into a suitable recess in the

instep-piece, and partly by means of a sliding bolt or catch *b*, which operates in a hole or recess *a'*, formed partly in the last-block body *A* and partly in the instep-piece *B*. Said bolt or catch normally extends partly in the portion *a'* and partly in the portion *b'* of the above-mentioned recess, and I connect it to the instep-piece *A* by means of a spring-wire *b*², which passes through it and is provided at its opposite end with an eye for the reception of a screw or tack *b*³. The bolt or catch *b* is made tubular for the reception of a flexible connecting-cord *b*⁴, which may be of any suitable material and held to said bolt by means of the spring-wire *b*², which passes through one end of it. The opposite end of said cord is fastened in any suitable manner to the last-block body *A*, in the present instance by being tightly held in a hole in said body by means of a wedge *a*². The instep-piece *B* is recessed to permit of the movement of the spring-wire *b*² away from the adjacent surface of said piece—as, for example, when the bolt *b* is pulled into the portion *b'* of the hole or recess by means of the cord *b*⁴—the normal position of the spring-wire being preferably that illustrated.

It will be seen that the bolt *b* and the pin *a* are so placed relatively to each other that the instep-piece *B* is tightly and firmly held in position when once it has been placed upon the last-block body by first entering the dowel-pin *a* into the recess of said piece, while permitting the bolt to be first moved into the portion *b'* of its recess and afterward to spring out of said recess into the part *a'* thereof when said two parts have been brought in line.

No ordinary force applied to the instep-piece is sufficient to detach it from the last-block body, though if it be desired that these pieces be taken apart—as, for example, in order to withdraw the structure from a shoe—an outward pull upon the cord *b*⁴ draws the bolt *b* into the portion *b'* of its recess and then results in the separation of said parts. Owing to the fact that the ends of the cord *b*⁴ are respectively attached to the two pieces *A* and *B* constituting the last-block body, these latter cannot be separated or mixed with the similar parts of other last-blocks.

I claim—

1. The combination of a last-block body,

an instep-piece, means for connecting said parts including a spring-actuated bolt carried by one of the parts, a cord having one end connected to one part of the last-bock, 5 and a spring-piece engaging the cord and arranged to fasten it to said sliding bolt so as to prevent the permanent separation of said parts, substantially as described.

2. A last-bock consisting of a body portion, 10 an instep-piece, a pin carried by one of said parts fitting in a recess in the other part, a tubular bolt carried by one of the parts and entering a suitable recess in the other, said bolt and pin being placed to tightly hold together said two parts, a spring attached to one of the parts and entering the tubular bolt, and a cord extending into the bolt and held therein by said spring, substantially as 15 described.

3. A last-block consisting of a body portion, 20 an instep-piece, a pin on one of the parts fitting in a recess in the other part, a second recess formed partly in one piece and partly in the other, a tubular bolt movable in said second recess, a spring-wire attached to one 25 of the parts of the block, and a cord connected to the other part, said cord extending through the second recess and into the tubular bolt and the spring extending into the bolt so as to engage and retain the spring in 30 position therein, substantially as described.

In testimony whereof I have signed my name to this specification in the presence of two subscribing witnesses.

JOHN A. RIHL.
